UNITED STATES PATENT OFFICE.

FRANCIS H. RICHARDS, OF HARTFORD, CONNECTICUT.

MECHANICAL MOVEMENT.

1,134,961.

Specification of Letters Patent.

Patented Apr. 6, 1915.

Application filed August 29, 1901, Serial No. 73,639. Renewed January 20, 1909. Serial No. 473,293.

To all whom it may concern:

Be it known that I, FRANCIS H. RICHARDS, a citizen of the United States, residing at Hartford, in the county of Hartford, and State of Connecticut, have invented certain new and useful Improvements in Mechanical Movement, of which the following is a specification.

This invention relates primarily to differential crank movements of the class made the subject-matter of my refiled application, Serial No. 71,159, filed August 17, 1901, in which two bearings, revolving about dissident axes, may, by means of a member which is articulated to both of said revolving members, and which is preferably in the form of an eccentric or other cam, impart irregular or uneven movement to another machine part; and it further relates to means for imparting diversified irregular movements to a plurality of machine parts, as set forth in my other pending application, Serial No. 29,749, filed September 12, 1900; and also to means for imparting to a coöperative member, at each revolution of a primary driver, two long reciprocal strokes and an intermediate contracted reciprocation, as set forth in my other pending application, Serial No. 72,099, filed Aug. 15, 1901.

One of the prime objects of the present invention is to substitute, for the circular movement of at least one of the two primary revolving members of a differential crank, an uneven orbital movement; and especially to alternately lift and depress the axis of one of the revolving crank-arms, so that the crank-pin thereon may describe a prolate orbit, preferably elliptical; whereby an operative member, preferably rigid with said crank-arm, may be caused simultaneously to revolve and reciprocate in a direction transverse to its axis of revolution; and whereby also the action of a transmission-bearing conjointly carried by the two variously revolving crank-arms may be considerably modified.

A further object is to enable diversely moving members, actuated respectively by said revolving and reciprocating crank-arm and said transmission-bearing, to coöperate to produce a result which depends partly upon the diversity of the movements of said crank-arm and said transmission or delivery bearing.

Other objects will hereinafter appear.

The specific form of the invention herein described is selected for the purpose of affording a clear illustration, and is not presented as the only form in which the invention may be applied.

In the accompanying drawings, Figure 1 is an end elevation, Fig. 2 is a side elevation, and Fig. 3 a plan of the preferred form of a mechanical movement embodying my present improvements. Fig. 4 is a diagram in which are plotted the successive periods or steps in the movements of the several members in the train of mechanism, and in which is also drawn an irregular curve which denotes the resultant of the coöperative movements of the several members of said train. Fig. 5 is a perspective view of a differential crank and a rocker frame whereon one of the primary members thereof is mounted. Fig. 6 is an enlarged diagram illustrating the relative initial positions of the several movement centers, and is explanatory of Fig. 1. Fig. 7 shows a form in which one portion of my improvements may be applied, another portion thereof being omitted.

In the several views, similar letters or numerals of reference designate corresponding parts.

A shaft 20, uniformly rotated by a pulley 21, is journaled in a standard 22 and carries a crank 23; and a shaft 24, carrying a crank 25, is journaled upon a support hereinafter described in detail, and is out of line with the shaft 20, said shafts being placed tandem, or end-to-end, and said cranks being mounted upon the adjacent ends thereof. From the free end of the crank 23 there projects a lateral bearing-pin 28, which, for convenience, will hereinafter be referred to as the primary driver. The crank 23 is coupled to the crank 25 by a device which is inserted between them and which preferably consists of a disk-like contrivance 30, having perforations for engaging both the journal 28 and a journal 29 provided upon the free end of the crank or arm 25. One of the functions of the linking member or coupler is to operate as an ordinary drag-link, whereby when the arm 23 is revolved the arm 25 is caused to follow, or vice versa; and, although susceptible of wide variation in its construction and method of mounting, said coupler is preferably made in the form of a biaxial eccentric-cam; that is, a circular disk or the like used as a cam, and hav-

ing its two movement axes each eccentric to its center of figure or periphery. Owing to its being conjointly carried by the variously revolving members 28 and 29, said eccentric-cam is given uneven movement, which may be transmitted by any suitable means, such as pitman 33, to any machine part whose movements are required to have irregularities. Thus the coupler is provided with at least three pivotal bearings, whereof two connect it to the revolving cranks and hence enable it to act as a drag-link, and whereof another forms the effective or movement-transmission portion of the coupler and enables it either to impart an uneven movement to a suitable transmitter, or to receive movement therefrom, as the case may be. Moreover, the crank 25, in my present improvements, forms another effective or movement-transmitting portion of the differential crank, and is preferably adapted to operate an instrument which co-operates with an instrument operated by the other effective portion 30 of the differential crank.

It being one of the main objects of the present improvements to impart a reciprocatory lateral movement to the revolving shaft 24, this is preferably journaled in a rocking-frame which is clearly depicted at Fig. 5, and may consist principally of two parallel forwardly-extending rocker-arms 34 and 35, in whose forward ends said shaft 24 is journaled, and also of an offset integral forwardly-extending arm 36. The arms 34 and 35 are rigidly connected by a rock-shaft 37, which is parallel with the revolving shaft 24, and is journaled in a standard 38, both of said standards 22 and 38 being erected upon a bed 39; and said offset arm 36 is preferably provided with a gudgeon 40 in line with the rock-shaft 37 and engaging a third standard 41, erected upon the bed. The arm 36 is connected with the remainder of the rocking frame by means of a bar 42, which is disposed in rear of the coupler 30, the latter working between the arms 35 and 36. By means of the rocking-frame, said revolving-shaft 24 may be lifted or depressed, thereby effecting an independent movement of the disk 30 about its axis 28, and consequently modifying the movement of the transmitter 29, and hence of any effective member driven thereby. Such lateral movement of the shaft 24 may also affect the operation of any instrument carried thereon or driven thereby. Any suitable means may be employed for reciprocating the frame, but preferably the arm 36 is provided at its forward end with a fork 43, which bestrides a small eccentric 44 fixed upon the driving-shaft 20, whereby the frame is lifted and depressed once in each revolution of said shaft, whereby the driven shaft 24 is caused to reciprocate laterally about the axis 37, and the bearing 29 is caused to revolve

through an uneven orbit, the degree of unevenness depending upon the eccentricity of the bearing 44. Preferably said orbit is elliptical, as indicated by the dotted curve 29^a at Fig. 4.

At Fig. 4 the circle 28^a describes the path of the driving-pin 28, while the dotted line A shows the direction or plane in which motion is transmitted through the coupler from the driver to the follower, and hence symbolizes the longitudinal axis of the drag-link. It will be borne in mind that the several members 28, 29, and 30 have a fixed relation to one another, so that as the parts 28 and 29 revolve in the direction indicated by the arrow, the central point or center of figure of the bearing 30 is caused to move in or trace the orbit 30^a, the transmitter connected thereto being actuated accordingly, together with a rocker-arm or other part 33^a, to which said transmitter may also be connected. The circle 28^a is divided, for convenience, into 16 equal intervals or time periods; while the orbit 30^a is divided into corresponding periods which are similarly numbered; whereby, when the driving-pin 28 stands at any of the points 1, 2, 3, 4, etc., on the circle 28^a, the bearing 30 stands at a point on the orbit 30^a which is marked with the same number.

Owing to the varying angles which line A assumes at different times with reference to the two cranks (indicated by the radial lines 23 and 25), the center 30 is caused to oscillate upon both of the revolving bearings 28 and 29, the gyration of said line A being caused partly by the diversity in the revolving movements of the arms 23 and 25, and partly by the independent lateral reciprocation of the shaft 24.

It will be perceived that the bearing 30 is not only caused to describe an irregular orbit, but is also sometimes accelerated and at other times is retarded in speed; thus, when the driver 28 is moving from point 1 to point 7 on the circle 28^a, or making considerably less than half of a revolution, the center 30 moves from 1 to 7 on the orbit 30^a, or substantially from the bottom to the top thereof, so that the transmitter 33 and the arm 33^a connected thereto are given approximately a full up-stroke, the first portion thereof being executed at higher velocity than the last portion. While the driver is moving from 7 to 10, taking half of the time required for the full up-stroke of the pitman 33, the center 30 moves across and down from 7 to 10 on the orbit 30^a. This orbit, it will be observed, is cordiform, and this portion of the movement is at the indented or cusp portion of the orbit, and the pitman 33 is so disposed that at this portion of the orbital movement it is given a contracted or curtate downward stroke. During the next eighth of a revolution of the primary driver, the center 30 moves out of the incurved por-

tion of the orbit, from 10 to 12, thereby giving the pitman 33 a curtate up-stroke, which is even shorter than the down-stroke just described. It will be perceived that during 5 the movement of the center 30 in the cusp portion of its orbit, its velocity is very low. While the primary driver is making the last five-sixteenths of its revolution, the center 30 makes substantially a full down-stroke, 10 from 12 to 1, the first portion of said stroke being at lower speed than the last portion thereof. At the upper portion of Fig. 4 the movements of several parts driven by the bearing 30 are also plotted and numbered. This irregularity or unevenness in 15 the movement of the transmitter 33, as compared to that obtained by means of the ordinary crank or eccentric, may be turned to a variety of uses, as, for instance, in the operation of pointed or other tools. Heretofore it has been the practice to effect machine movements of this variety by means of irregularly-shaped cams, which are difficult to construct and are more or less noisy 20 and unsatisfactory in operation, as well as otherwise objectionable; whereas, by this invention, the movement may be effected by means of easily-made, smooth-running and durable circular or pivotal bearings. The 25 invention is not, however, limited to the use of circular delivery bearings in all cases. It will be perceived, therefore, that a uniform and regular movement may be converted directly into an uneven orbital movement, the bearing or eccentric 30 being caused to trace its orbit by reason of the compound movement which it derives partly from the circularly-revolving crank-pin 28 and partly from the elliptically-revolving 30 crank-pin 29. The movement of the bearing 30 is partly due to the position occupied by its own center of figure with relation to both of said pins. It will also be observed at Fig. 4 that the crank-pin 29 revolves at variable angular speed in the elliptical orbit 29^a. For instance, while the driver 28 is making one-half of a revolution, the follower 29 moves through less than half of the ellipse 29^a, or from 1 to 9, the last 35 portion of this movement being at lower velocity than the first portion thereof; and while the driver 28 is completing its revolution, said follower 29 makes more than half of its revolution, from 9 to 1, its velocity 40 during certain periods of this movement being considerably greater than during other portions.

The diversely driven members 29 and 30 may be caused to coöperate in various ways, 45 one of which is illustrated in the drawings. The arm 33^x, operated by the pitman 33, may be connected by a rock-shaft 45, mounted in a boss projecting from a vertically extended portion 38^a, of the standard 38, 50 and a rock-arm 46 upon said shaft may be

connected by a link 47 to a vertically sliding device 48, carrying at its lower end a pencil or other pointed tool 49, the latter being preferably adapted to trace a line upon the vertical face of a disk 50, mounted upon the opposite end of the crank-shaft 24 from the crank 25. This disk symbolizes a work-holder or controller, and may hence be considered as a revolving instrument; and it will be understood that this instrument may 70 be otherwise formed and mounted and may perform other functions with relation to the work than that illustrated; as for instance, it may carry a pencil, and the work may be mounted either upon the slide 48, or otherwise. 75

At each revolution of the driving-shaft 20, each member of the set of devices driven by the bearing 30, makes a complete cycle of movements, while the disk 50 is given by 80 the crank 25 an unevenly-timed complete revolution, and is simultaneously given by the eccentric 44, through the rocking-frame, an up-and-down reciprocation. An irregular curve is thus generated by the pencil 49 85 upon the work carried upon the disk 50, which curve is in the form of an oblate cordiform curve 49^a, although other curves may be produced by varying the mechanism. The divisions 1 to 16 upon said resultant 90 curve 49^a correspond with the similarly-marked divisions on the primary circle 28^a and the ellipse 29^a. It will be seen that the 95 velocities of the variously moving members 49 and 50 are extremely variable; for instance, while the primary driver is making one-fourth of a revolution, from 16 to 4, the pencil 49 is nearly stationary, while the follower 29 makes somewhat less than one-fourth of a revolution, and the rocker-frame 100 (indicated at 35, Fig. 4) makes about one-third of its down-stroke; and upon the further comparison of the various lines at said figure, other variations will be perceived. Thus, by reciprocating the support of the 105 crank 25, variations are effected, not only in the movements of the transmission-bearing 30 and of the parts driven thereby, but also in the movements of the coöperative instrument carried upon or connected to the 110 crank shaft 24.

Referring now to Fig. 7, it will be seen that the members 28 and 29 are positively connected by a simple drag-link A', which is in this instance not provided with a third bearing, although the position of the eccentric-cam 30 is indicated by a dotted line. The parts operated by said cam are also omitted, the mechanism being used only for the purpose of moving the instrument 50 or 120 125 50^x in a particular manner. I intend in certain of the following claims to cover certain features illustrated at Fig. 7, whether employed independently of the remaining features of the invention or not. 130

Changes of course may be made within the scope of the invention, and some parts of my improvements may be employed without some others. Some of the following 5 claims are limited to the specific form of the invention herein illustrated; while others thereof are intended to cover the invention broadly when it is practised in other ways or with other accessories.

10 Having described my invention, I claim:

1. The combination of two revoluble members positively connected by a linking member having a motion compounded of an angular and a translational motion; supports 15 for said revoluble members; means for reciprocating one of said supports in such a manner as to cause the member mounted thereon to revolve in an elliptical orbit; and a transmission-bearing provided upon said 20 linking member and movable in a prolate cordiform orbit.

2. The combination of a driving shaft having a fixed axis; an offset shaft placed tandem to said driving-shaft; arms mounted 25 upon the adjacent ends of said shafts; an angularly and translationally movable linking member inserted between said arms and journaled thereon, and provided with a pivotal transmission member eccentric to both 30 of its journals; and means controlled by said driving-shaft for reciprocating the driven shaft automatically in a lateral direction.

3. The combination of two horizontal 35 shafts provided with crank-arms; an angularly and translationally movable coupler journaled upon said arms, and provided with a dissident pivotal transmission-bearing; a hinged device whereon one of said 40 shafts is mounted; and an eccentric-cam rigid with one of said shafts and actuating said hinged device.

4. A differential crank comprising two 45 revoluble members, whereof one moves about a laterally reciprocating axis which is always eccentric to the axis of revolution of the other member; and also comprising a biaxial eccentric-cam journaled at its eccentric axes upon said revoluble members and linking them together.

5. A differential crank comprising two 55 revoluble members, whereof one turns about a laterally swinging axis, and a biaxial eccentric-cam journaled at its eccentric axes upon said revoluble members and linking them together.

6. A differential crank comprising two 60 revoluble members, whereof one revolves upon an axis which a lateral reciprocal movement once in each revolution of the other member; and also comprising a biaxial eccentric-cam articulated to said revoluble members.

7. The combination of a device revoluble

about a fixed axis; a device revoluble about 65 a laterally movable axis; a biaxial eccentric-cam journaled at its eccentric axes upon said revoluble devices; means positively connected to said first revoluble device for imparting a lateral reciprocation to said movable 70 axis; and a movement-transmitter engaging said eccentric-cam.

8. The combination of two revoluble members linked together by a biaxial eccentric-cam; supports for said revoluble members; means for reciprocating one of said supports in such a manner as to cause a member mounted thereon to revolve in an elliptical orbit; and a movement-transmitter 75 engaging said eccentric-cam. 80

9. The combination with two devices revoluble upon parallel axes, of a biaxial eccentric-cam linking them together; automatically operating means for effecting a lateral reciprocation of one of said revoluble devices about a third parallel axis; and an endwise-movable transmitter engaging 85 said eccentric-cam.

10. The combination of the two revoluble devices placed side by side; a biaxial eccentric-cam inserted between said revoluble devices and journaled thereon at its eccentric axes; automatically reciprocating means for causing one of said revoluble devices to move in a distorted orbit; and a movement- 90 transmitter 95 engaging said eccentric-cam.

11. The combination of two revoluble shafts; arms mounted thereon; a biaxial eccentric-cam journaled upon said arms; means actuated by one of said shafts for 100 producing a relative lateral reciprocal movement between said shafts; and a movement-transmitter engaging said eccentric-cam.

12. The combination of a driving-shaft 105 having a fixed axis; an offset shaft placed tandem to said driving-shaft; arms mounted upon the adjacent ends of said shafts; a biaxial eccentric-cam inserted between said arms and journaled thereon; means controlled by said driving-shaft for reciprocating the driven shaft in a lateral direction; and a pitman mounted upon said eccentric-cam. 110

13. The combination of a device revoluble 115 upon a fixed support; a revoluble device mounted upon a hinged support; a biaxial eccentric-cam journaled upon said devices; means positively connected to one of said revoluble devices for swinging said support 120 to and fro upon its hinge; and a pitman mounted upon said eccentric-cam.

14. The combination with two shafts, of supports therefor; arms carried upon adjacent ends of said shafts; a biaxial eccentric-cam journaled upon the ends of said arms; a device upon which one of said supports is hinged; means for enabling one of said 125

shafts to swing said hinged support to and fro; and a movement-transmitter engaging said eccentric-cam.

15. The combination of two revoluble members, a biaxial eccentric-cam journaled upon said members, a stationary support for one of said revoluble members, a hinged support for the other of said revoluble members means including a cam for automatically swinging said hinged support to and fro, and a movement-transmitter engaging said biaxial eccentric-cam.

16. The combination of two horizontal shafts provided with crank-arms; an angularly and translationally movable biaxial eccentric-cam coupling said arms; a hinged device whereon one of said shafts is mounted; a single eccentric-cam rigid with one of said shafts and connected to said hinged support; and a movement-transmitter engaging said biaxial eccentric-cam.

17. A differential crank comprising two journaled revoluble constraining members, whereof one moves about a laterally reciprocating axis, and also a linking member journaled upon said revoluble members and provided with a dissident transmission-bearing which is caused by said revoluble constraining devices alone to move in a cordiform orbit.

18. A differential crank comprising two journaled revoluble members arranged side by side, whereof one turns upon an axis which reciprocates laterally about a third axis; and also comprising a member guided by and articulated to said revoluble members and gyrated thereby in such a manner that a transmission-bearing carried upon said articulated member is caused to move in a cordiform orbit.

19. The combination with two devices revoluble upon parallel axes, of a linking member journaled upon said devices and provided with a pivotal transmission-bearing; automatically operating means for effecting a lateral reciprocation of one of said revoluble devices about a third parallel axis; the construction and arrangement of the several members being such that said transmission-bearing is caused to move in a cordiform orbit; and a movement-transmitter engaging said transmission-bearing and driven thereby in a direction which approximately agrees with a diametrical line which bisects the cusp portion of said orbit.

20. The combination with two revoluble shafts, of arms mounted thereon; a linking member journaled upon said arms and carrying a dissident transmission-bearing; means actuated by one of said shafts for producing a relative lateral reciprocal movement of one of said shafts; the construction and arrangement of the several parts being such that said transmission-bearing is

caused to move in a cordiform orbit; and an endwise-movable transmitter engaging said transmission-bearing and given thereby four reciprocal strokes at each orbital revolution thereof.

21. The combination of a device revoluble upon a fixed support; a revoluble device mounted upon a hinged support; a coupler journaled upon said devices and provided with a dissident pivotal transmission-bearing which is caused by said revoluble devices to move in a cordiform orbit; means positively connected to one of said revoluble devices for swinging said support to and fro upon its hinge; and a pitman mounted upon said transmission-bearing and given thereby two long reciprocal strokes and a curtate reciprocation at the termination of one of said long strokes.

22. The combination with two shafts, of supports therefor; arms carried upon adjacent ends of said shafts; a linking member journaled upon the ends of said arms and provided with a delivery bearing which is eccentric to its journals; a device upon which one of said supports is hinged; means for enabling one of said shafts to swing said hinged support to and fro; the construction and arrangement of the several parts being such that said delivery bearing is caused to move in a cordiform orbit; and a pitman mounted upon said delivery bearing and driven thereby in a direction which approximately agrees with a diametrical line which bisects the cusp portion of said orbit.

23. A differential crank comprising two revoluble members, whereof one moves about a laterally reciprocating axis, and also a biaxial eccentric-cam journaled at its eccentric axes upon said revolving members and caused thereby to move in a cordiform orbit; in combination with a movement-transmitter engaging said eccentric-cam.

24. A differential crank comprising two revolving members, whereof one turns about a laterally swinging axis, and also comprising a biaxial eccentric-cam journaled at its eccentric axes upon said revolving members; in combination with an endwise-movable movement-transmitter engaging said eccentric-cam.

25. The combination of a device revoluble about a fixed axis; a device revoluble about a laterally movable axis; a biaxial eccentric-cam journaled at its eccentric axes upon said revoluble devices; means positively connected to said first revoluble device for imparting a lateral reciprocation to said movable axis; the construction and arrangement of the several parts being such that said eccentric-cam is caused to move in a cordiform orbit; and a pitman mounted upon said eccentric-cam.

26. The combination of two revoluble

members linked together by a biaxial eccentric-cam; supports for said revoluble members; means for reciprocating one of said supports in such a manner as to cause the member mounted thereon to revolve in an elliptical orbit, and said eccentric-cam to move in a prolate cordiform orbit; and a pitman mounted upon said eccentric-cam and given thereby four reciprocal strokes at each revolution thereof.

27. The combination of two devices revoluble upon parallel axes, of a biaxial eccentric-cam linking them together; automatically operating means for effecting a lateral reciprocation of one of said revoluble devices about a third parallel axis; the construction and arrangement of the several parts being such that said eccentric-cam is caused to move in a cordiform orbit; and a movement-transmitter engaging said eccentric-cam and given thereby two long reciprocal strokes and a curtate reciprocation at the termination of one of said long strokes.

28. The combination of a uniformly revolving driver; a variably revolving instrument having a single-link connection to said driver said link-connection having a motion compounded of an angular and a translational motion; a hinged support for said instrument; and means positively connected to said driver for reciprocating said support upon its hinge; the axis of revolution of said instrument being constantly eccentric to the axis of revolution of said driver.

29. A differential crank comprising two revoluble members, whereof one moves about a laterally reciprocating axis which is always eccentric to the axis of revolution of the other member; and also a linking member journaled upon said revoluble members and provided with a dissident delivery bearing; in combination with a sliding pointed instrument positively connected to said delivery bearing.

30. A differential crank comprising two members revoluble upon horizontal axes, one of said axes executing an up-and-down movement once in each revolution, and also comprising a delivery drag link member 50 conjointly carried by said two revoluble members; in combination with a vertically sliding member positively connected to said delivery member and given thereby irregularly-timed reciprocal movements.

31. The combination of a driver revoluble about a fixed axis; a follower revoluble about a laterally movable axis; a drag-link journaled upon said revoluble devices and provided with a dissident delivery bearing; means for enabling said driver to impart a lateral reciprocation to said follower; an instrument rigid with said follower; and a coöperative instrument actuated by said delivery bearing.

32. The combination of a revoluble driver;

a revoluble instrument; means, including a linking member, for connecting said instrument to said driver; a support for said revoluble instrument; means for reciprocating said support once during each revolution 70 of said instrument; a delivery bearing provided upon said linking member and caused to move in a prolate cordiform orbit; and a coöperative instrument operated by said delivery bearing.

75
33. The combination of a revoluble driver; an instrument revoluble upon an axis which is parallel with the driver axis; means, including a linking member, for connecting said instrument to said driver; a delivery 80 bearing provided upon said linking member and moving in an uneven orbit; automatically reciprocating means for effecting a lateral reciprocation of said instrument about a third parallel axis; and a coöperative instrument positively connected to said delivery bearing.

85
34. The combination of a revoluble driver; a revoluble shaft carrying an arm; a linking member journaled upon said driver and said 90 arm and provided with a dissident delivery bearing; an instrument mounted upon the opposite end of said shaft; means controlled by said driver for producing a lateral movement of said shaft; and a coöperative instrument actuated by said delivery bearing.

95
35. The combination of a driving-shaft having a fixed axis; an offset shaft placed tandem to said driving-shaft; arms mounted upon the adjacent ends of said shaft; a linking member inserted between said arms and journaled thereon and provided with a delivery bearing which is eccentric to both of its journals; means controlled by said driving-shaft for reciprocating the driven shaft 100 in a lateral direction; an instrument mounted upon the opposite end of said driven shaft so as to revolve and reciprocate therewith; and a coöperative instrument reciprocated by said delivery bearing.

110
36. A differential crank comprising two revolving members, whereof one is a driver and the other revolves upon an axis which executes a lateral reciprocal movement once in each revolution, and also comprising a 115 biaxial eccentric-cam articulated to said revolving members; in combination with an instrument rigid with said laterally reciprocating member, and a coöperative sliding instrument connected to said biaxial eccentric-cam.

120
37. The combination of a driver revoluble about a fixed axis; a driven member revoluble about a laterally movable axis; a biaxial eccentric-cam journaled at its eccentric axes 125 upon said revoluble devices; means positively connected to said driver for imparting a lateral reciprocation to said driven member; an instrument rigid with said driven member; a movement-transmitter engaging 130

said eccentric-cam; and a coöperating instrument driven by said movement-transmitter.

38. The combination of two members revoluble upon horizontal axes and linked together by a biaxial eccentric-cam; supports for said revoluble members; means for reciprocating one of said supports in an up-and-down direction in such a manner as to cause the member mounted thereon to revolve in an elliptical orbit; an instrument rigid with said elliptically moving member; a movement-transmitter engaging said eccentric-cam; and a vertically sliding tool operated by said movement-transmitter.

39. The combination with a driver and a follower revoluble upon parallel axes, of a biaxial eccentric-cam linking them together; automatically operating means for effecting a reciprocation of said follower about a third parallel axis; an instrument rigid with said follower; an endwise-movable transmitter engaging said eccentric-cam; and a coöperative instrument connected by a rock-shaft to said transmitter.

40. The combination of a driving-shaft; a driven shaft; arms mounted upon said shafts; a biaxial eccentric-cam mounted upon said arms; means actuated by one of said shafts for reciprocating said driven shaft in a lateral direction; an instrument mounted upon the end of said driven shaft; a movement-transmitter engaging said eccentric-cam; and a coöperative reciprocatory instrument connected to said movement-transmitter.

41. The combination of a driver revoluble upon a fixed support; a follower mounted upon a hinged support; a biaxial eccentric-cam journaled upon said driver and follower; means positively connected to one of said driver and follower elements for causing said follower support to swing to and fro upon its hinge; a pitman mounted upon said eccentric-cam; a sliding pointed instrument connected by a rock-shaft to said pitman; and a coöperative instrument operated by said follower.

42. The combination with a driving-shaft and a driven shaft, of supports for said shafts; arms carried upon the adjacent ends of said shafts; a biaxial eccentric-cam journaled upon the ends of said arms; a device upon which the support for said driven shaft is hinged; means for enabling one of said shafts to swing said hinged support to and fro; an instrument mounted upon said driven shaft; a movement-transmitter engaging said eccentric-cam; and an instrument reciprocated by said eccentric toward and from the axis of said driven shaft.

43. The combination of a revoluble driver; a revoluble follower; a biaxial eccentric-cam journaled upon said driver and

follower; a hinged support for said follower; means for automatically swinging said hinged support to and fro; an instrument mounted to revolve and swing with said follower; and a coöperative instrument sliding vertically toward and from the axis of said follower.

44. The combination of a driving-crank; a shaft upon which is mounted a follower-crank; a biaxial eccentric-cam coupling said cranks; a hinged device whereon said follower-shaft is mounted; a cam connected to said driver for causing said hinged device to swing up and down; a pitman mounted upon said biaxial eccentric-cam; and a vertically sliding pointed instrument connected by a rock-shaft to said pitman and working approximately in a line which is radial to the axis of said follower-shaft.

45. A differential crank comprising a revoluble member, a member revoluble in an unevenly curved orbit, and also a linking member articulated to said revoluble members, said linking member having a circular transmission-bearing which is eccentric to its articulations upon said revoluble members, and which is also caused by said revoluble members to move in a cordiform orbit; in combination with an instrument rigid with the second of said revoluble members; and a coöperative instrument which is given two long reciprocal strokes and a curtate intermediate reciprocation by said transmission-bearing.

46. A differential crank comprising two revoluble members, whereof one moves about a laterally reciprocating axis, and also a linking member journaled upon said revoluble members and provided with a dissident transmission-bearing which is caused by said revoluble members to move in a cordiform orbit; in combination with an instrument given a four-stroke reciprocal movement by said transmission-bearing.

47. A differential crank comprising two revoluble members arranged side by side, whereof one turns upon an axis which reciprocates laterally about a third axis; and also comprising a member inserted between and articulated to said revoluble members and gyrated thereby in such a manner that a transmission-bearing carried upon said articulated member is caused to move in a cordiform orbit; in combination with a vertically sliding instrument which is given by said transmission-bearing two long reciprocal strokes and an intermediate curtate reciprocation.

48. The combination of two revoluble devices placed side by side; a linking member inserted between said revoluble devices and journaled upon both thereof, and provided with an eccentric pivotal transmission-bearing; automatically reciprocating means for causing one of said revoluble de-

vices to move in a distorted orbit; the construction and arrangement of the several parts being such that said transmission-bearing is caused to move in a cordiform orbit; a movement-transmitter engaging said transmission-bearing and given thereby two long reciprocal strokes and a curvate reciprocation at the termination of one of said long strokes; a sliding pointed instrument actuated by said movement-transmitter; and a coöperative instrument actuated directly by the revolute device which moves in a distorted orbit.

49. The combination with two revolute shafts, of arms mounted thereon; a linking member journaled upon said arms, and carrying a dissident transmission-bearing; means actuated by one of said shafts for producing a relative lateral reciprocal movement of one of said shafts; the construction and arrangement of the several parts being such that said transmission-bearing is caused to move in a cordiform orbit; an endwise-movable transmitter engaging said transmission-bearing and given thereby four reciprocal strokes at each orbital revolution thereof; a tool controlled by said transmitter; and a coöperating instrument mounted upon said laterally-reciprocating shaft.

50. The combination of a device revolute upon a fixed support; a revolute device mounted upon a hinged support; a coupler journaled upon said devices and provided with a dissident pivotal transmission-bearing which is caused by said revolute devices to move in a cordiform orbit; means positively connected to one of said revolute devices for swinging said support to and fro upon its hinge; a pitman mounted upon said transmission-bearing and given thereby two long reciprocal strokes and a curvate reciprocation at the termination of one of said long strokes; an instrument rigid with the revolute device which is mounted upon said hinged support; and an instrument caused by said cam to reciprocate toward and from the axis of revolution of said instrument.

51. A differential crank comprising two revolute members, whereof one moves about a laterally-reciprocating axis, and also a biaxial eccentric-cam journaled at its eccentric axes upon said revolving members and caused thereby to move in a cordiform orbit; in combination with a movement-transmitter engaging said eccentric-cam; an instrument rigid with a member which revolves upon the up-and-down reciprocating axis; and a vertically sliding tool-holder arranged above said instrument and connected to said eccentric-cam; the axes of movement of all of said elements being horizontal.

52. The combination of a horizontal driv-

ing-shaft; a horizontal following-shaft placed tandem thereto but out of line therewith; arms upon the adjacent ends of said shafts; a biaxial eccentric-cam linking said arms together; a horizontally hinged support for said follower-shaft; means for enabling said driving-shaft to swing said hinged support in an up-and-down direction; an instrument mounted upon the opposite end of said follower-shaft; a pitman mounted upon said eccentric-cam; a rock-shaft connected by an arm to said pitman; and a vertically sliding tool arranged over said follower instrument and connected by a link and an arm to said rock-shaft.

53. The combination of a horizontal driving-shaft; a horizontal following-shaft placed tandem thereto but out of line therewith; arms upon the adjacent ends of said shafts; a biaxial eccentric-cam linking said arms together; a horizontally hinged frame upon which said follower-shaft is journaled; a cam fixed upon said driving-shaft and forked by a member provided upon said hinged frame; a work-controller mounted upon the opposite end of said follower-shaft; an upwardly-extending pitman mounted upon said eccentric-cam; a horizontal rock-shaft to which the upper end of said pitman is connected; a vertically sliding holder arranged over said work-controller and connected by a link and an arm to said horizontal rock-shaft; and a pointed instrument carried by said holder.

54. The combination with two devices revolute upon parallel axes, of a biaxial eccentric-cam linking said devices together; automatically-operating means for effecting a lateral reciprocation of one of said revolute devices about a third parallel axis; the construction and arrangement of the several parts being such that said eccentric-cam is caused to move in a cordiform orbit; a movement-transmitter engaging said eccentric-cam and given thereby two long reciprocal strokes and a curvate reciprocation at the termination of one of said long strokes; a pointed tool operated by said movement-transmitter; and an instrument rigidly connected to the revolute device which is reciprocated about said third axis.

55. The combination with a bed, of a horizontal shaft having a support thereon; a parallel shaft driven thereby; a hinged support for said driven shaft; means for automatically reciprocating said hinged support; an instrument mounted upon said driven shaft; arms mounted upon the adjacent ends of said shafts; a coupler conjointly carried by said arms, and provided with a dissident delivery bearing; a vertical slide positively connected to said delivery bearing; and a device erected upon said bed for supporting said slide.

56. The combination of a driving-shaft

20; following - shaft 24; arms 34 and 35 mounted upon a rock-shaft 37, and rocking said shaft 24; offset arm 36, rigid with said arms and forking a cam 44, mounted upon said shaft 20; arms 23 and 25 erected upon the adjacent ends of the shafts 20 and 24; and a member linking together said arms 23 and 25.

57. The combination of two revoluble members positively connected, a fixed support for one of said members, an irregularly rocking support for the other of said members, whereby changes may be effected in the relative positions of the respective axes of revolution of said members, and a vertically reciprocating pointed tool non-uniformly driven by a member which links said shafts together.

58. The combination with two positively connected devices revoluble in vertical planes, of a horizontally-disposed bearing

for one of said devices, a horizontally-hinged support for the other of said devices, means for imparting once in each revolution a non-uniformly-timed reciprocal movement 25 to said hinged support, and a vertically sliding tool connected by a horizontal rock-shaft to a member which links said revoluble devices together.

59. A differential crank comprising two 30 revoluble members, whereof one moves about a non-uniformly reciprocating axis which is always eccentric to the axis of revolution of the other member, and also comprising a biaxial eccentric-cam journaled at 35 its eccentric axes upon said revoluble members and linking them together, and a tool operated by said eccentric-cam.
